United States Patent Office

Des. 185,486

Patented June 16, 1959

185,486

TRAY FOR DRILL PRESS OR THE LIKE

Preston P. Boblett, Springfield, Ohio, assignor to Pan-M-Bob Manufacturing Corporation, Springfield, Ohio, a corporation of Ohio

Application April 21, 1955, Serial No. 35,622

Term of patent 7 years

(Cl. D55—1)

The figure is a perspective view of a tray for drill press or the like embodying my design.

I claim:

The ornamental design for a tray for drill press or the like, substantially as shown.
